UNITED STATES PATENT OFFICE.

HENRY T. DAWSON AND HENRY ALFRED DAWSON, OF CANTERBURY,
ENGLAND.

INTERNAL-COMBUSTION MOTOR.

SPECIFICATION forming part of Letters Patent No. 651,780, dated June 12, 1900.

Application filed July 10, 1899. Serial No. 723,400. (No model.)

To all whom it may concern:

Be it known that we, HENRY THOMAS DAWSON and HENRY ALFRED DAWSON, subjects of the Queen of Great Britain, residing at 5 Canterbury, in the county of Kent, England, have invented certain new and useful Improvements in Internal-Combustion Motors, of which the following is a specification.

Our invention relates to internal-combustion motors, either gas or oil, and has for its object to provide means for starting, for augmenting the power, for promoting the exhaustion of the waste gases, and for reversing when required.

15 In the accompanying drawings, Figure I is an elevation, mostly in section, of a motor constructed according to our invention. Figs. II, III, and IV show various positions of the augmenting and non-return valves. Fig. V 20 is a plan, partly in section, of the slide-valve-reversing gear. Fig. VI is a vertical section of the starting-valve. Fig. VII is a plan, partly in section, showing three motors coupled together.

25 Like numerals refer to like parts in all the figures, which are drawn to various scales.

To attain our objects, we provide the motor with two cylinders 2 3, hereinafter referred to as the "combustion-cylinder" and the 30 "air-cylinder," respectively. The two cylinders are arranged in line and the air-cylinder forms an enlarged continuation of the combustion-cylinder. They may be cast in one piece or built up. The two pistons 4 5 are 35 preferably in one piece, as shown, the combustion-piston 4 being continued and enlarged to form an annular air-piston 5. They are preferably both connected to the one crank 6 by the piston-rod 119, though they may be 40 separate or connected to the same or separate cranks, if desired. The combustion-cylinder is fitted with the usual admission and exhaust valves 7 and 8, respectively, and some suitable ignition device, and the motor 45 works normally on the Otto cycle.

The air-cylinder 3 is fitted with a slide or other valve 10, as on a steam or compressed air-engine. This valve works synchronously with the crank-shaft 11 and is fitted with a 50 reversing-gear, hereinafter described, so that this part of the motor will on the application

of fluid pressure drive either forward or backward, or, if mechanically driven, it will act as a pump in either direction.

The air-cylinder is employed for three purposes—first, to compress air through the pipe 12 into the reservoir 13 up to a pressure determined by an adjustable safety-valve 14, which is mounted on the said pipe between the engine and the reservoir; secondly, on 60 admission of the compressed air from the reservoir (or of other fluid-pressure) to the air-cylinder the piston 5 therein will be moved and the motor started, and, thirdly, the air-cylinder is employed to pump air into the combustion-cylinder 2 in such a way as both to assist in the expulsion of the waste gases and also to increase the quantity of pure air in the charge, and hence its working pressure.

In addition to the slide-valve 10 or other 70 mechanically-worked valve above referred to the air-cylinder is fitted with a valve 15, (hereinafter referred to and which normally acts as a "non-return valve"), which may also be operated by hand. The face of this valve is 75 preferably recessed to increase the area on which the air may act when lifting it, thus reducing the back pressure when charging the air-reservoir. All the air pumped from the air-cylinder 3 passes this valve 15 through 80 the port 25, whether on its way to the reservoir 13 or to the combustion-cylinder 2; but when the said valve and the starting-valve, hereinafter referred to, are opened by hand the air returns under pressure into the air-cylinder 3 and actuates its piston 5 to start 85 the motor or increase its power. A port 16 opens from the non-return-valve box 17 into the combustion-cylinder at such a point that it is only opened by the piston 4 at the end of 90 the said piston's outward stroke. A third valve 18, hereinafter referred to as the "augmenting-valve," covers the port 16 where it opens into the said valve-box 17 and is jointed (131) to the tail 19 of the non-return valve 95 15, so that both valves 15 and 18 may be worked together through the rod 20 by the hand-lever 21, pivoted at 22; but the parts are so proportioned and arranged that if the handle be set in its middle position both the 100 non-return valve 15 and the augmenting-valve 18 will cover their respective ports 16

and 25 at the same time, as shown at Figs. I and II, when air will be pumped from the air-cylinder 3 through the pipe 12 into the reservoir 13, the valve 15 lifting to allow of this. If when the motor is at rest the handle be set back, the augmenting-valve will still cover its port 16; but the non-return valve 15 will be opened, Fig. III, and (provided the starting-valve also be opened) the compressed air will return from the reservoir through the pipe 12 and port 25 and act on the piston 5, so as to start the motor. If the valve-handle 21 be set forward, the augmenting-valve 18 will be opened and the non-return valve 15 will be closed, so that all the air passing through the non-return valve from the air-cylinder enters the combustion-cylinder 2 at the end of each outstroke of its piston 4. The air which so enters at the end of the explosion-outstroke drives out most of the burned gases through the exhaust-valve 8 before the said piston commences its exhaust-instroke, and at the completion of the exhaust-instroke what remains in the combustion-chamber is nearly pure air. At the completion of the next (*i.e.*, the suction) outstroke another supply of air from the air-cylinder enters the combustion-cylinder, where it augments the charge just sucked in, thus raising the compression-pressure and also the resulting combustion-pressure, more combustible material being also added to mix with the augmented air charge. The non-return valve 15 and the augmenting-valve 18 cannot both be open at the same time. The non-return valve 15 is fitted with a weak spring and the augmenting-valve 18 is fitted with a strong spring. Both springs may be formed, if desired, from one blade 50, as shown, (though this is not essential,) the one end of the spring being turned over and provided with a pin 128 to engage in a recess 129 in the back of the augmenting-valve 18 and insuring that the spring shall travel with the said valves and the other end of the spring being received between lateral guides 130 on the back of the non-return valve 15. Two of such springs are preferably employed, one on each side of the tail 19 of the valve 15.

Any suitable kind of reversing-gear may be used to convert the air-cylinder from a pump to a motor or to reverse its direction as a motor; but we prefer to employ the device shown in Fig. V, wherein an eccentric disk 26, having a non-circular hole 27 passing obliquely therethrough, is mounted between two guides 28, which prevent lateral motion, while leaving it (26) free to move in its own plane. This eccentric disk is mounted on a shaft 29, the parts 30, adapted to slide through the oblique hole 27, being made of corresponding section and set at the same angle as such hole, so that by moving the shaft lengthwise the eccentricity of the disk may be altered or reversed as required. The longitudinal movement of the shaft 29 may be effected by any suitable means, such as a hand-lever 31, car-

rying a spur-pinion or sector 32, concentric with its fulcrum 33, the teeth of the pinion or sector engaging with the annular teeth of a rack 34, turned upon the end of the shaft. The rod 35, Fig. I, working the slide-valve 10 of the air-cylinder 3, is connected to the strap 36, surrounding the eccentric disk 26. The shaft 29, carrying the eccentric, is driven at the same speed as the crank-shaft 11 by a chain running over the chain-wheels 38 39, fixed thereto, respectively, or by other positive gear. When the handle 31 is set over to the left, the engine drives forward. When the handle is set over to the right, the eccentricity of the disk 26 is reversed and the engine drives backward, and when the handle is set in the middle position, as shown in full lines, the disk 26 assumes a position concentric with the shaft 29, the valve-rod 35 and valve 10 remaining stationary, and the pneumatic portion of the motor is rendered ineffective, the engine working as a combustion-motor only. On another shaft 40, Fig. I, driven at half the speed of the crank-shaft 11 through the shaft 29 by the two-to-one gear 41 42, a cam 43 is mounted directly in line with the axis of the exhaust-valve 8. The said valve is acted on by the cam through the medium of a roller 44 and is normally held closed by a suitable spring 45, which also carries the said roller, preferably no transmission-levers being employed. The exhaust-valve is made of large bulk to prevent its overheating. The cam-shaft or the cam itself on the shaft has sufficient backlash to enable it to assume the rightly-timed position for opening the exhaust-valve in whichever direction the engine may be running.

The admission-valve 7 is of the well-known automatic mushroom type. An elastic tongue or lever 46 is pivoted at 47 with its upper end in the path of the lower end of the non-return-valve hand-lever 21, so that when setting the handle back for starting the admission-valve is automatically raised slightly from its seat and the compression is temporarily relieved. When a certain speed has been attained, the pressure of the elastic tongue is overcome, the admission-valve closes, and full compression is obtained. The closing of the non-return valve 15 by moving forward the handle 21 allows the tongue to withdraw from the admission-valve spindle.

The air pumped into the reservoir passes through a second non-return valve, hereinafter referred to as the "starting-valve" 48, Fig. VI. This starting-valve is normally automatic, being provided with a light tension-spring 51, which allows the air to be pumped through the pipe 12 into the reservoir 13. To facilitate this action, the valve proper, 52, is connected to its spindle 53 by a pin-and-slot device 54, so that the valve 52 can be opened by air entering the reservoir without moving the spindle 53 in its gland 55. As soon as the pumping of the air from the cylinder 3 into the reservoir 13 ceases the valve is closed

by its spring 51; but in order to start the engine the valve 52 can be lifted from its seat against the reservoir-pressure and the spring 51 by the handle 49, thus allowing the compressed air to rush back from the reservoir into the air-cylinder behind the piston 5.

The engine may be constructed so that the cylinders 2 3, being cast in one piece, practically form the frame, while the crank-shaft 10 bearings 120 are carried by stanchions 121, which also serve as bolts for the combined bearing-caps and frame-supports 122. Any number of these engines may be coupled together on one crank-shaft, the stanchions carrying the bearings 120 at one end and at the other end passing through lugs 123 on the cylinders, arranged so as to lock together each pair of adjacent cylinders, as shown in the plan, Fig. VII. With this construction 15 the valve-shafts 29 and 40 are made long enough to serve all the cylinders and all the air-cylinders pump into a single reservoir through a common main 124, while the non-return 15 and augmenting valves 18 are 20 united by a rock-shaft worked by the single hand-lever 21. All the eccentrics 26 may be altered or reversed simultaneously by the rack-and-pinion device 32 34 already described. If three motors be so coupled together, their cranks are arranged at one hundred and twenty degrees and their other parts are correspondingly arranged relatively to one another, so that the crank-shaft 11 may be started or reversed from any position in 30 which it may have come to rest without any possibility of its sticking on a dead-center.

Referring more particularly to the plan, Fig. VII, the commutator 114, with its insulating-shield 9 for connecting up the sparking-plugs 115 at the right intervals, will be seen at one end of the half-speed shaft 40, and close by is the contact-breaker ring 97, which in this case will have three detents 98 at one hundred and twenty degrees apart. This 40 shaft carries the exhaust-cams 43 and at its other end the large spur-wheel 41, which meshes with the small wheel 42 of the two-to-one gear. Rigidly connected to the spur-wheel 42 is a sprocket-wheel 38, both being secured to the eccentric-shaft 29 by the feather 126, so that the said shaft may move axially through the said wheels without allowing of independent rotary motion of the parts. The wheel 38 is driven from the wheel 50 39 of equal size on the crank-shaft 11 through a suitable pitch-chain, so that the shafts 11 and 29 necessarily rotate at the same speed. The angular parts 30 of the shaft 29 are set in planes situated at angles of one hundred 55 and twenty degrees to each other, and the rack 34 and pinion 32, by which all three slide-valves 10 are simultaneously operated, will be seen at the end of this shaft.

The right-hand motor is shown as cut 60 through in the plane of the lower facing of the slide-valve 10, the double lines indicat-

ing the position of the box of this valve. The valve 10 itself is shown in nearly the same position as in Fig. I, the right crank 125 being about thirty degrees below the horizontal 70 backward. The center motor is shown as cut through in the plane of the upper facing of the augmenting-valve 18 and non-return valve 15, the jointing of the tail 19 of the latter to the back of the former being clearly indicated. The recesses 129 and guides 130 for the valve-springs are also visible. The position of these valves corresponds to that shown in Fig. IV and the middle crank 125 is vertically upright. The left-hand motor is complete, and above it is shown part of the air-main 127, with which the pipe 12 communicates. The corresponding crank 125 is thirty degrees below the horizontal forward. The circulating-pump communicating with the 85 water-jackets 124 would be placed at this end of this crank-shaft 11 outside the sprocket-wheel 39 and the oil-pump and governor would be placed at the other end of the said shaft. 90

The action of the engine is as follows: On the first occasion of starting the crank-shaft 11 is turned by the fly-wheel or handle (not shown) until a compression and explosion are obtained; but this is not necessary on future 95 occasions unless insufficient compressed air is left in the reservoir. On restarting the engine the handle 21 is pulled back to close the augmenting-valve 18 and open the non-return valve 15, at the same time slightly opening the admission-valve 7 to ease the compression. The handle 31 is set over to the left or right, according to the direction in which it is desired that the engine shall drive, the oil or gas supply is opened, and then the lever 49 is depressed to open the valve 48, whereupon some of the compressed air stored in the reservoir 13 rushes through the pipe 12 and port 25 to act upon the air-piston 5, which it moves forward. The engine being thus 100 started, the oil or gas feed and the ignition devices are brought into operation and after a few strokes of the pistons 4 5 the starting-lever 49 may be released, when the engine will be driven by the explosion of the vaporized oil, and on placing the reversing-lever 31 opposite to the direction in which the engine is running air will be compressed into the reservoir 13. After the engine has been running some time, the lighter oil, such as 105 petrol, may be turned off and the heavier oil, such as paraffin, may be turned on. When the reservoir is sufficiently charged, the handle 31 may be set in either its middle or its forward position, when no more air will be 110 pumped. Increase of power is obtained by setting the handle 21 forward, so as to open the augmenting-valve and the reversing-lever 31 against the engine's motion, when the piston 5 will pump air into the combustion-chamber, increasing the charge for explosion 115 at one instroke and clearing out the waste 120 petrol. The handle 31 may be set in either its middle or its forward position, when no more air will be 125 pumped. Increase of power is obtained by setting the handle 21 forward, so as to open the augmenting-valve and the reversing-lever 31 against the engine's motion, when the piston 5 will pump air into the combustion-chamber, increasing the charge for explosion 130 at one instroke and clearing out the waste

4
gases at the next instroke, and so on. This method of increasing the power is more particularly meant for temporary use—as, *e. g.*, in climbing hills. To reverse the engine, the handle 31 is moved to the position opposite to that in which it was placed at starting.

We do not confine ourselves to the above-described minor details, nor do we make any claim thereto. Among other purposes our motors are very suitable for the propulsion of autocars or motor-cycles.

What we claim, and desire to secure by Letters Patent of the United States, is—

1. In an internal-combustion motor, the combination of, a combustion-cylinder; an air-cylinder forming an enlarged continuation of the combustion-cylinder; a combustion-piston; an annular air-piston in one with the combustion-piston; a crank-shaft; a piston-rod connecting the piston and crank-shaft; an admission-valve; an exhaust-valve; an ignition device; a valve-box; a port opening from the valve-box into the combustion-cylinder; a port opening from the air-cylinder 25 into the valve-box; an air-reservoir communicating with the said valve-box; a valve fitted to said reservoir normally adapted to admit air into said reservoir and prevent its return therefrom; a non-return valve located 30 in the said valve-box and adapted to open and close the port opening from the air-cylinder into the valve-box; and means for moving the said non-return valve by hand; substantially as and for the purposes set forth.
2. In an internal-combustion motor, the combination of, a combustion-cylinder; an air-cylinder forming an enlarged continuation of the combustion-cylinder; a combustion-piston; an annular air-piston in one with the 35 combustion-piston; a crank-shaft; a piston-rod connecting the piston and crank-shaft; an admission-valve; an exhaust-valve; an ignition device; a valve-box; a port opening from the valve-box into the combustion-cylinder; a port opening from the air-cylinder 45 into the valve-box; an air-reservoir communicating with the said valve-box; a valve fitted to said reservoir normally adapted to admit air into said reservoir and prevent its return 50 therefrom; a non-return valve located in the said valve-box and adapted to open and close the port opening from the air-cylinder into the valve-box, an augmenting-valve also located in the said valve-box, connected to the 55 non-return valve and adapted to open and close the port opening from the valve-box into the combustion-cylinder; and means for moving the said non-return and augmenting valves by hand, substantially as and for the 60 purposes set forth.
3. In combination, the non-return valve 15, the augmenting-valve 18; the tail 19 on the non-return valve jointed to the augmenting-valve; the ports 16 and 25; the pivoted hand-

lever 21; and the rod 20 connecting the augmenting-valve 18 and the hand-lever 21, substantially as and for the purpose set forth.

4. In combination, the valve-box 17; the non-return valve 15; the augmenting-valve 18; a recess 129 in the back of the augmenting-valve; a blade-spring 50 having one end turned over; a pin 128 on the said turned-over end of the blade-spring adapted to engage in the said recess; and lateral guides 130 on the back of the said non-return valve adapted to receive the other end of the said non-return valve, substantially as and for the purpose set forth.

5. In an internal-combustion motor, the combination with the cylinder, piston, piston-rod, crank-shaft and valve, of a shaft rotatable at the same speed as the crank-shaft; a non-circular portion of the said shaft set at an angle to the length of such shaft; a disk; a non-circular hole passing obliquely through 85 said disk and adapted to receive the said non-circular portion of the shaft with a sliding fit; lateral guides for the said disk; a strap surrounding said disk; a rigid connection between said strap and the said valve; means for moving the said shaft in the direction of its length; and means for rotating the said shaft; substantially as and for the purpose set forth.

6. In an internal-combustion motor, the combination with the cylinder, piston, piston-rod, crank-shaft and admission-valve, of a shaft rotatable at half the speed of the crank-shaft; an exhaust-valve; a spring adapted to close the said exhaust-valve; a roller carried by the said spring and adapted to bear on the said exhaust-valve; a cam mounted on the said shaft, having a limited backlash relatively to the crank-shaft and adapted to bear on the said roller; and means for rotating the 105 said shaft, substantially as and for the purpose set forth.

7. In an internal-combustion motor, the combination with an automatic admission-valve, of a pivoted lever; an elastic tongue carried by the said lever and adapted to press open the said admission-valve; and means for operating the said pivoted lever, substantially as and for the purpose set forth.

8. In an internal-combustion motor, the combination with an automatic admission-valve, of a pivoted lever; an elastic tongue carried by the said lever and adapted to press open the said admission-valve; and a pivoted hand-lever adapted to operate on the said 115 pivoted lever, substantially as and for the purpose set forth.

HENRY T. DAWSON.

HENRY ALFRED DAWSON.
